To all whom it may concern:

Be it known that we, CHARLES H. BUCK and WILEY S. WRIGHT, of St. Louis, in the county of St. Louis and State of Missouri, have produced a new and original Design for a Cook-Stove; and we do hereby declare that the following is a specification:

The nature of our design is fully represented in the accompanying photographic illustration, which is a perspective view of the stove, showing the front and one side thereof.

The side of the stove presents three doors, each having a central ornament in relief surrounded by a molding. The ornament in the

center of the largest one of these doors is the figure 6. The front of the stove presents, above the hearth, two doors, each having in its center the letter B. Below the hearth is a panel surrounded by a molding, and at the front vertical corners of the stove are pillars.

We claim as our invention—
